US0D1077883S

(12) **United States Design Patent** (10) **Patent No.:** **US D1,077,883 S**
(45) **Date of Patent:** **** Jun. 3, 2025**

(54) **IP CAMERA**

(71) Applicant: **SHENZHEN APICAL TECHNOLOGY CO., LTD.**, Shenzhen (CN)

(72) Inventors: **Zhengzhong Yu**, Shenzhen (CN); **Guangping Lin**, Shenzhen (CN); **Wendong Gao**, Shenzhen (CN); **Fuchi Li**, Shenzhen (CN)

(73) Assignee: **SHENZHEN APICAL TECHNOLOGY CO., LTD.** (CN)

(**) Term: **15 Years**

(21) Appl. No.: **29/900,582**

(22) Filed: **Aug. 22, 2023**

(51) LOC (15) Cl. **16-01**

(52) U.S. Cl.

USPC **D16/202**

(58) **Field of Classification Search**

USPC D16/200, 202, 203; D14/125, 474, 496; D10/104.1

CPC H04N 2101/00; H04N 23/531
